UNITED STATES PATENT OFFICE.

LOUISE B. FELDMAN, OF MINNEAPOLIS, MINNESOTA.

EMBROIDERING AND BEADING DEVICE.

Application filed June 24, 1925. Serial No. 39,254.

This invention relates to an embroidering and beading device comprising an implement adapted to be held in one hand of the operator and used in embroidering cloth or 5 fastening beads to cloth, which cloth, preferably will be in stretched condition, as, for instance, on an embroidery hoop. A great deal of embroidering and beading work is now done on dress goods and other articles 10 and it is desirable that this work be easily and rapidly performed.

It is an object of this invention, therefore, to provide a device for embroidering and beading, comprising a small shank adapted 15 to be held in one hand of the operator, which device has its upper end curved laterally so as to fit over the forefinger of the operator, the device having a thin sharp point at its upper end below which is a laterally and 20 downwardly extending curved hook forming a recess, said recess being adapted to be closed by a swinging pointed tongue which overlaps the lower and outer side of said hook when in its upper position and which 25 is substantially received in the side of said device when in its lower position.

It is a further object of the invention to provide such a device, as above set forth, 30 which is tapered to form a narrow neck portion adjacent its upper end, the curved portion of the device being above the neck portion and of larger diameter than the neck portion.

These and other objects and advantages 35 of the invention will be fully set forth in the following description made in connection with the accompanying drawings in which like reference characters refer to the same parts throughout the different views, and in 40 which,

Fig. 1 is a view of the device showing the same in operative relation to a piece of cloth in which an embroidered chain stitch has been made;

Fig. 2 is a view of the reverse side of a portion of cloth shown in Fig. 1, showing the other side of the portion shown in Fig. 1 and also illustrating a line of beading secured thereto by the device of the present 45 invention;

Fig. 3 is a view in side elevation of the device with its swinging tongue in a different position;

Fig. 4 is a view in front elevation of the 50 upper end of the device;

Fig. 5 is a view in side elevation of Fig. 4,

a portion of the device being shown in vertical section; and

Fig. 6 is a horizontal section on the line 6-6 of Fig. 5, as indicated by the arrow, 60 Figs. 4, 5 and 6, being shown on an enlarged scale.

Referring to the drawings, the same is illustrated as comprising a shank portion 7. While this portion may be of various shapes, 65 in the embodiment of the invention illustrated, is shown as cylindrical in form and of a size adapted to conveniently be held in the hand. The portion 7 tapers towards its upper end to form a narrow neck portion 7^a and 70 has an enlarged portion 7^b above said neck portion. The enlarged portion is curved laterally, as clearly shown in Figs. 1, 3 and 5 and terminates in a thin sharp pointed portion 7^c. At the bottom of the portion 7^c, 75 a hook 7^d extends laterally and downwardly, which hook is curved and also formed with a sharp point and also forms a recess 7^e. Below the recess 7^e the portion 7^b is provided with a slot 7^f in which is disposed one 80 end of a swinging tongue 8 secured by a pivot rivet 9 to the portion 7^b at each side of slot 7^f. It will be seen that the tongue 8 is curved and pointed and when in its upper position, slightly overlaps the outer side 85 and lower end of the hook 7^d, as shown in Fig. 5. The tongue 8, when in its lower position, fits in and is substantially received in the lower part of slot 7^f, as shown in Fig. 3.

In operation, in making an embroidery 90 stitch, such as a chain stitch, the goods 10 will be stretched on the frame, such as embroidery hoop and the end of the thread 11 will be drawn through the fabric at the desired point. The device 7 is then held in 95 the hand of the operator and pushed through the cloth 10 from the bottom side which is the side shown in Fig. 1. When the device is pushed upward through the cloth the point of the tongue 8 engages the cloth and 100 is swung down to the position shown in Fig. 3. The device is thus easily passed through the cloth and the narrow portion 7^a is brought into the plane of the cloth. This portion is made narrow or of small 105 diameter so that the cloth will not be unduly stretched or an unnecessarily large hole made therein, in the movement of the device. The operator now moves the thread or holds the thread so that the hook 7^d can be 110 engaged thereover and the thread disposed in the recess 7^e. The device is now pulled

downward through the cloth and the lower end of the tongue 8 again engages the cloth so that it is swung to its upward position, as shown in Fig. 5. The device is now easily pulled down through the cloth and pulls the thread therewith. The operator again presses the device upward through the cloth at the desired distance from the point where it was last passed through the cloth to form the proper length of stitch. The thread is not removed from the recess 7^e while the device is below the cloth so that the loops 11^a are formed on the underside of the cloth but the straight portions or stitches 11^b are formed on the upper side of the cloth. A straight and regular embroidery stitch is thus made on the upper side of the cloth. The stitch is of the chain type and can be readily pulled out. The stitch at either side of the cloth can be used in embroidering, as desired. In using the device, the skilled operator has the upper end of the device lying or pressed against the front of the forefinger. In order to use the implement to the best advantage it is desirable to have the upper end of the device curved as shown, so as substantially to fit the curve of the forefinger. With this curve in the implement, the same also will be more comfortable in operation and have less tendency to mark or callous the finger. The curved upper end of the device enables the same to bear over a larger surface of the finger or thumb in the operation of the device, thus making the operation more comfortable. Also, by having the upper end of the device or hook 7^e may be kept nearer to the surface of the goods with less swinging or angular movement of the device than if the same were straight. If a curved needle swings upward through the plane of the goods with a swinging movement somewhat concentric with its center of curvature, the point will move in an arc and the curvature will result in the point staying nearer the surface of the goods. If a straight device or needle is pushed through the goods, the point, of course, will move in a line angular to said plane and thus away from said plane. With such a straight needle it would be necessary to give the same an angular movement to bring the point nearer said plane or make it approach the surface of said goods. With a curved needle or device this angular movement is unnecessary. The upper end of the device is made with a very thin sharp point so that it will readily pass through the goods and will not make an unnecessarily large hole therein. The hook 7^a is thus made to extend laterally from the portion 7^e so that the portion 7^e can be made thinner and the

goods more easily pierced. The tool is, of course, quite smooth, especially at the sides adjacent the ends of the rivet 9. The upper 65 end of the tool, beyond the neck portion 7^a in the drawing is about three times the actual size of the device.

In using the device for beading, the thread 12 will have the beads 12^a thereon and as 70 the device is pushed upward through the goods the thread 12 in between the beads will be engaged in the recess 7^e and drawn downwardly through the goods, a chain stitch being formed, as previously described. 75 The beads 12^a are thus firmly and neatly secured in place.

From the above description it is seen that applicant has provided a very simple and efficient device for use in hand work in 80 embroidering and beading. The device has been amply demonstrated in actual practice and found to be very successful and efficient. While some devices with swinging tongues have been used for needles in knitting 85 machines, these knitting machine needles are not suitable for hand work. The same usually have wide points more-or-less blunt and the needles are, of course, attached to a frame on the machine. The present device is a 90 hand implement adapted for a different use and also in a different art and the narrow neck portion 7^a thereof and the laterally curved end are features adapting it for use in its particular art. 95

It will, of course, be understood, that various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claim. 100

What is claimed is:

An implement for embroidering and beading comprising a shank adapted to be held in one hand and being tapered to have a narrow neck portion of comparatively small cross-sectional area adjacent its upper end, 110 said device having an enlarged laterally curved portion above said neck portion terminating in an elongated narrow sharp point to penetrate the fabric and having a laterally and downwardly directed curved hook 115 on its convex side below said first mentioned point forming a recess and a curved pointed swinging tongue adapted to overlap the lower end of said hook and fit into the side of said enlarged portion when swung downwardly. 120

In testimony whereof I affix my signature.

LOUISE B. FELDMAN.
